COMBINED CLOCK RADIO AND SWIVEL BASE THEREFOR

Hachiro Masuda, Lodi, and Morris J. Feldman, North Caldwell, N.J., assignors to York Radio Corp., South Hackensack, N.J.

Filed Aug. 6, 1970, Ser. No. 42,345

Term of patent 14 years

Int. Cl. D14—03; D10—01
U.S. Cl. D42—7

FIG. 1 is a perspective view of a combined clock radio and swivel base therefor showing our new design, with the clock radio member swiveled forward;

FIG. 2 is a right side elevational view with the clock radio in normal alignment;

FIG. 3 is a left side elevational view thereof;

FIG. 4 is a top plan view thereof;

FIG. 5 is a bottom plan view thereof;

FIG. 6 is a front elevational view thereof; and

FIG. 7 is a rear elevational view thereof.

We claim:

The ornamental design for a combined clock radio and swivel base therefor, as shown.
